CLAIM

The ornamental design for a display screen or a portion thereof with a digital pay statement, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first embodiment of a display screen or a portion thereof with a digital pay statement showing a first image in a sequence;

FIG. 2 is a second image thereof;

FIG. 3 is a front view of a second embodiment of a display screen or a portion thereof with a digital pay statement showing a first image in a sequence; and,

FIG. 4 is a second image thereof.

The outer broken lines showing a display screen or a portion thereof in all views are for the purpose of illustrating environment and form no part of the claimed design. The remaining broken lines show portions of the digital pay statement that form no part of the claimed design. The appearance of the animated images sequentially transitions between the images shown in FIGS. 1-2 or FIGS. 3-4. The process or period in which one images transitions to another forms no part of the claimed design.
